Primary Examiner — Mitchell I. Siegel

CLAIM

The ornamental design for a golf tee, as shown and described.

DESCRIPTION

FIG. 1 is a perspective view of a golf tee in accordance with my new design;

FIG. 2 is a left side view of golf tee as shown in FIG. 1;
FIG. 3 is a right side view of golf tee as shown in FIG. 1;
FIG. 4 is a top view of golf tee as shown in FIG. 1;
FIG. 5 is a bottom view of golf tee as shown in FIG. 1;
FIG. 6 is a front view of golf tee as shown in FIG. 1; and,
FIG. 7 is a back view of golf tee as shown in FIG. 1.

The broken lines in the figures depict portions of the golf tee in which the design is embodied that forms no part of the claimed design.

1 Claim, 2 Drawing Sheets
